(57) **CLAIM**

The ornamental design for a weightlifting machine, as shown and described.

DESCRIPTION

FIG. 1 is a top, front, left perspective view of a weightlifting machine showing my new design;

FIG. 2 is a top, rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent to the shaded area define the bounds of the claimed design and form no part thereof. The broken lines depicting the remainder of the weightlifting machine show features that form no part of the claimed design.
